UNITED STATES PATENT OFFICE.

HAYDEN H. HALL, OF NEW HAMBURG, ASSIGNOR OF ONE-HALF TO RICHARD H. BULL, OF NEW YORK, N. Y.

SEGMENT FOR CONSTRUCTING TUNNELS.

SPECIFICATION forming part of Letters Patent No. 341,002, dated May 4, 1886.

Application filed April 13, 1885. Serial No. 162,140. (No model.)

To all whom it may concern:

Be it known that I, HAYDEN H. HALL, a citizen of the United States, and a resident of New Hamburg, in the county of Dutchess and State of New York, have invented certain new and useful Improvements in Segments for Constructing Tunnels and Tubes, of which the following is a specification.

My invention consists, first, of a tunnel frame or shell composed of a series of non-corrosive segmental plates consisting of white cast chilled metal made with flanges, the flanges of each segment being provided in casting with bolt-holes to correspond with each other, by which the several segments are bolted together to form the tunnel-shell of the desired form; and my invention consists, second, of molded tubular segmental plates composed of white cast chilled metal made with projecting flanges having molded bolt-holes therein, by which a series of them can be bolted together to form a tunnel tube or pipe.

The following is a description of my improved tunnel frame or shell and of the segmental plates composing it, the points of novelty being designated by the claims concluding this specification.

In the drawings, Figure 1 is a vertical cross-sectional view of a mold having a segmental plate therein. Fig. 2 is a longitudinal sectional view thereof. Fig. 3 is an end view, and Fig. 4 a side elevation, of a completed segmental plate. Fig. 5 is a longitudinal, and Fig. 7 a transverse, section of a tunnel frame or shell made upon the plan of my invention. Fig. 6 is a longitudinal elevation of the same.

It has heretofore been proposed to make the shell or frame of submarine tunnels of segments or sections of cast or wrought iron, the several segments and sections being bolted together in a manner very similar to that adopted by me; but the method and material heretofore used in the construction of the segmental plates have resulted in the production of a worthless tube or tunnel frame.

The segments being made of wrought or cast iron, and having the holes drilled for the uniting-bolts, such a tunnel frame or shell is easily constructed, but corrosion sets in at once, and in a short time it is consumed or practically destroyed by rust, either in salt or fresh wa-

ter; but by making the shell or tube of molded segments composed of white cast-iron, having the bolt-holes made in the operation of molding and casting, and the whole chilled, the resulting tube is substantially non-corrosive, and will endure indefinitely. Such a shell or tube is readily made in the manner illustrated.

In the drawings, A is the body of a segment, made of white cast chilled metal, the turned edge B of the segment having holes D cast therein, for the purpose set forth. In casting the segments I use a heavy cast-iron mold consisting of bottom E, provided with perforated lugs F, which extend through perforations in the sides G, also made of heavy cast metal, and are secured in place by wedges or pins H. A heavy cast-iron top piece or frame, I, provided with depending edge J, fits around the top of the mold, and is filled with molding-sand K, forming the inner shape of the segment provided with filling and vent holes, as indicated.

L are cores of compressed plumbago or other suitable substance, fitting into holes in the sides of the molds, said cores leaving the holes D in the segment.

There is scarcely any limit to the durability, strength, length, and size of tunnel that may be constructed upon this plan, and the shell may be made single or double, as may be required, the intervening space being filled with brick, laid in cement or other suitable filling.

In molding the segments provision is preferably made to form grooves in the adjoining faces of the flanges to receive a non-corrosive packing or cement that will form a water-tight joint between the several plates as they are put together to form the tube, and in joining the plates bolts and nuts should be used that have been thoroughly galvanized, thus making the whole structure non-corrosive, the principal object of the invention being to make a submarine tunnel of metal that can be readily and cheaply produced and put together, and that can be made of any desired strength and size, and that shall be practically non-corrosive.

Having now fully described my invention, what I claim as new therein, and desire to secure by Letters Patent, is—

1. A segment made of white cast chilled metal, having inwardly-extending edges with holes therein for securing said segments togeth-

er to form a tunnel or water-pipe, substantially as shown and described.

2. A segment for constructing tunnels or water-pipes, said segments being constructed of white cast metal chilled in casting, and having holes formed therein for securing the segments together, substantially as shown and described.

3. A submarine tunnel or tube consisting of non-corrosive cast-iron constructed of segmental plates composed of such iron, having inter-

nal flanges and bolt-holes, by which the several sections are tied together to form the tunnel or tube, substantially as described.

Signed at New York, in the county of New ¹⁵ York and State of New York, this 2d day of April, A. D. 1885.

HAYDEN H. HALL.
